UNITED STATES PATENT OFFICE.

WILLIAM CLARK DENNIS, OF LITCHFIELD, MINNESOTA.

CLOTHES-TONGS.

1,060,898.

Specification of Letters Patent.

Patented Dec. 9, 1913.

Application filed October 7, 1911. Serial No. 653,429.

To all whom it may concern:

Be it known that I, WILLIAM CLARK DENNIS, a citizen of the United States, residing at Litchfield, in the county of Meeker and 5 State of Minnesota, have invented certain new and useful Improvements in Clothes-Tongs, of which the following is a specification.

This invention relates to improvements in 10 devices of the class adapted to grasp articles of clothing, cloths or similar products where it is desired to lift said articles without having the hands of the operator come in contact with the articles or the fluids in 15 which the articles have been immersed.

The device which forms the subject matter of this application for patent is especially adapted for lifting clothes from the boiling water in a wash boiler or from the 20 hot water in a washing machine so that the user of the device will not be obliged to subject his or her hands to contact with the hot water. It is also adapted for use in 25 handling articles of clothing which have been recently dyed and are saturated with the dyeing fluid.

The especial object of the improvements embodied herein is to produce a device which costs little to make and at the same 30 time provides effective means for gripping and holding the articles clamped by the device so that they will not drop or come in contact with the hands of the operator.

A further object is to provide a gripping 35 device that will not readily become heated from contact with the hot water in which the articles of laundry are submerged.

A still further object is to provide a device that will be extremely durable and 40 which may be used for any purpose requiring the handling of flexible material within the gripping limitations of the device.

In the drawing:—Figure 1 is an elevational view of the device in its open or 45 operative position; Fig. 2 is a similar view showing the device in operative position, and—Fig. 3 is a fragmentary view in plan of the gripping ends of the device.

The device constructed as shown is made 50 from a single piece of wire of suitable gage and temper for the uses for which the finished product is intended. If the article is for gripping small pieces of fabric for use in cleaning lamp chimneys, it will be understood 55 that the device will be made in proportion

and the wire will be relatively small. If, however, the article is intended for use in connection with laundry operations or dye vat operations, it will be considerably larger, heavier and stronger.

The single wire of which the device is constructed is bent upon itself to form two arms which are connected by a coil 4. The wire in each of said arms is then spirally wound with the helices of varying diameter 60 so as to provide the tapering gripping portions 5 in the middle of the arms. The wire of one of the arms is then bent inwardly to form an offset shoulder 6 at an angle to the arm and then bent to form a loop 7 elliptical in general contour, and is again bent at the base of the loop to form a shoulder 6^a parallel with the shoulder 6 and the free end of the wire is coiled around the portion of the arm remaining between the 65 shoulders 6, 6^a, and the handle 5 as shown at 8 and is extended through the coil 5. The wire of the other arm of the device is bent almost identically like the arm above 70 described except that the loop 9 is sufficiently larger in diameter than the loop 7 to permit the latter to pass through the loop 9 as far as the oppositely inwardly 75 projecting shoulders 6, 6^a, will permit.

The device will be constructed of tempered wire so that the coil 4 will form an 80 expansion spring the normal tension of which will be to expand or separate the two arms of the device to the position shown in Fig. 1. If it be desired to grasp a piece of cloth 85 or an article of clothing with the device, the loops 7 and 9 will be pushed on opposite sides of the article and the handles 5 will be brought together by the operator with sufficient pressure on the two arms to cause the loop 7 to pass through the loop 9. If the fabric is thin and the article small 90 the loop 7 and the fabric which it engages will pass through the loop 9 as indicated in Fig. 2, but if the fabric is heavy this movement of the loop 7 will be limited but in any event the gripping action of the two loops 95 will be sufficient to prevent the fabric or article of clothing from slipping between the loops or jaws of the gripping device.

The inwardly bent shoulders 6, 6^a, and the twisted shanks 8 stiffen and strengthen the arms so that wire of relatively small gage may be used for lifting heavy articles.

The form of the handles 5 facilitates

keeping the device cool by reason of the large radiating surface but such handles are, of course, well known in the art.

I am aware that various devices of this nature have been patented embodying gripping jaws and coöperating handles and I do not therefore broadly claim such a construction but

What I claim and desire to secure by Letters Patent, is:-

1. A gripping device of the character described, consisting of a single piece of wire bent to form connected handle portions and gripping loops the loops being so proportioned and arranged that one will pass

through the other when the loops are brought into operative position.

2. A gripping device, consisting of a single piece of wire bent midway its length to form a coil, and each section of wire from said coil bent to form a spiral and a loop and twisted to form a rigid portion connecting the loop with the spiral.

In testimony whereof I affix my signature in the presence of two witnesses.

WILLIAM CLARK DENNIS.
